WRIST WATCH

Cyril C. Gsell, Port Chester, N.Y., assignor to R. Gsell & Company, Inc., New York, N.Y., a corporation of New York

Filed Oct. 10, 1969, Ser. No. 19,501

Term of patent 14 years

Int. Cl. D10—02

U.S. Cl. D42—1

FIG. 1

FIG. 2

FIG. 3

FIG. 4

FIG. 6

FIG. 5

FIG. 1 is a top plan view of a wrist watch showing my new design wherein the earth representation serves as the hour indicator, the command module representation serves as the minute indicator, and the lunar landing module representation serves as the seconds indicator;

FIG. 2 is a bottom plan view thereof;

FIG. 3 is a side elevational view thereof;

FIG. 4 is a fragmentary sectional view on line 4—4 of FIG. 1;

FIG. 5 is a top plan view of a wrist watch showing another form of my new design wherein the command module representation serves as the hour indicator and the lunar landing module representation serves as the minute indicator; and

FIG. 6 is a fragmentary sectional view on line 6—6 of FIG. 5.

I claim:

The ornamental design for a wrist watch, as shown and described.
